UNITED STATES PATENT OFFICE

LOUIS V. ARONSON, OF NEWARK, NEW JERSEY

RECEPTACLE WITH REMOVABLE JACKET

Application filed April 26, 1928. Serial No. 272,977.

The invention relates to receptacles, with particular reference to cigar or cigarette lighters, and has as an object the provision of a removable decorated jacket for such receptacles whereby receptacles may be made in quantity and a variety of jackets of different appearance may be kept in stock, with the object of enabling the stock receptacles to be provided with a jacket supplying any desired finish to fill an order.

It is a further object of the invention to provide a receptacle having a surface presenting a color or appearance differing from the general appearance of the jacket, and providing openings in the jacket to enable the surface of the receptacle to show therethrough.

Further objects of the invention will appear from the following description when read in connection with the accompanying drawing showing an illustrative embodiment of the invention, and wherein

Fig. 1 is a side view of a complete device.

Fig. 2 is a vertical transverse section on line 2, 2 of Fig. 1.

Fig. 3 is a perspective view of the jacket-retaining plate.

Fig. 4 is a perspective view of a receptacle with the jacket and plate omitted, and

Fig. 5 is a perspective view of one form of jacket.

As shown, the device comprises a receptacle 10, desirably formed with a lower annular flange 11, and a retaining plate 12 which, when applied to the receptacle 10, will provide an upper retaining flange 13. A jacket is shown at 14 which is shaped to outwardly and telescopically fit upon the receptacle 10.

A jacket 14 of a desired outer finish may be chosen for any of the like receptacles 10 in stock, and may be slipped thereon, after which the plate 12 is placed upon the upper end of the receptacle, and may be retained thereon, as by means of a screw 15, passing through a perforation 16 in the plate and

extending into an internally threaded socket 17, carried by the upper surface of the receptacle.

In the embodiment of the invention disclosed, the plate 12 is shown as provided with an opening 18 for passage of a wick tube 19 and slots 20 and 21 for passage of the standards 22, 23 designed to carry the spark-producing mechanism of the igniter, with an opening 24, to pass the pyrophoric element 55 holding tube 25 of the lighter, and with an opening 26 to pass the tube 27 in which the means for operating the spark protecting mechanism may seat.

A plurality of jackets 14 will be kept in stock which may be enameled or polished, and may be made of different materials, as silver, gold, enameled brass or the like, whereby stock receptacles 10 may have the desired finish readily applied thereto.

To further ornament the finished article, the receptacle 10 is shown in Fig. 4 as provided with a surface 28 which may be of different appearance from that of the jacket to be applied, and the jacket may be provided with an opening, or openings 29, to allow the surface 28 to show therethrough.

In the form shown in Fig. 5, the openings 28 are so applied as to outline an initial letter.

In use the receptacle 10 and the operating mechanism may be made stock without regard to the desired finished appearance of the article, and an unlimited number of jackets 14 carrying different finishes may also be carried in stock. When an order is received for lighters of a definite finish, jackets of the finish desired may be taken from stock, assembled with the receptacles 10, and the order may be readily filled without keeping in stock a large number of complete igniters finished in the multitude of finishes which may be desirable.

Minor changes may be made in the physi-

cal embodiment of the invention without departing from the spirit thereof.

I claim—

- 5 A lighter comprising, in combination, a fuel receptacle comprising a side wall, an end wall secured thereto and projecting laterally therebeyond to provide a flange and a top wall secured to the side wall flush with the surface thereof, mechanism supporting
10 means projecting from said top wall, a cover plate having openings through which said supporting means project and formed with a marginal flange overlapping said side wall, a removable jacket of distinctive appearance
15 slipped over said side wall and confined between said bottom flange and said cover flange, and means to secure said cover plate to said top wall.
